UNITED STATES PATENT OFFICE.

ALEXANDER FLEMING, OF CEDAR RAPIDS, IOWA.

REINFORCEMENT FOR CEMENT CONSTRUCTIONS.

1,081,700.

Specification of Letters Patent.

Patented July 9, 1912.

Application filed September 7, 1911. Serial No. 648,235.

To all whom it may concern:

Be it known that I, ALEXANDER FLEMING, a citizen of the United States, residing at Cedar Rapids, in the county of Linn and 5 State of Iowa, have invented certain new and useful Improvements in Reinforcements for Cement Constructors; and I do declare the following to be a full, clear, and exact description of the invention, such as will enable others skilled in the art to which it appertains to make and use the same.

This invention relates to reinforcements for cement constructions, and is more particularly adapted for the completion of 15 fence posts or other structures capable of withstanding the rough usage to which the same are necessarily subjected.

The present application embodies an improved construction on my former application for patent for a similar invention filed Aug. 6, 1911, Serial No. 576,017, whereby the general construction of the post is improved by the employment of truss wires enveloping the entire structure and having 25 their ends interlockingly engaged with the ends of the bars forming a part of the structure for the purpose hereinafter described.

The primary object of the invention is therefore, in the formation of a metallic 30 skeleton frame or structure which is light, durable and effective for the purpose, the parts being bindingly and properly assembled in such a manner that when the cement is combined therewith in the final 35 completion of the post, or structure, a perfect and uniform construction is produced.

Briefly stated the invention consists in the employment of angle bars which are uniformly connected in their proper position 40 in respect to one another by binding bands properly positioned along the length of the bars and connected to one another, and crossing and separately arranged truss wires extending from the opposite ends of the 45 frame and bindingly in contact with the outer edges of said bars and also in contact with the bands, the opposite upper and lower ends of said bars being notched at their medial portions to receive the opposite 50 connected ends of the truss wires, the lower ends of the latter projecting inwardly and having upwardly projecting hooks forming yielding anchors which are embedded in the cement during the final completion of the 55 post.

With these and other objects in view, the

invention consists of certain novel features of construction, and the combination and arrangement of parts as will be more fully described and claimed.

In the accompanying drawings: Figure 1 is a vertical side elevation of the complete invention; Fig. 2 is a transverse horizontal section on the line 2—2 of Fig. 3; Fig. 3 is a vertical section showing a fragmental portion of the lower end of the structure; and, Fig. 4 is a perspective view showing one of the angle bars employed in carrying out the invention.

In the illustrative embodiment of the invention, 1 represents a series or plurality of angle bars which are preferably three in number and angularly positioned in respect to one another for properly and uniformly constructing the post for the purpose herein-after described. The post when completed is preferably triangular in cross section, the bars of which the same is composed being connected and properly spaced in respect to one another by a series of bands, 2 and 3, arranged in pairs and engaging with the inner and outer surface of the bars at predetermined distances along the length of said bars, the bands thus arranged being connected and bindingly brought into engagement with the bars by clips 4 which are folded around the bands thus arranged, all of which is clearly shown in Fig. 1 of the drawing. The opposite upper and lower ends of the bars 1 are inclined as shown at 5, forming notches 6 at the medial portions thereof for the purposes now to be described.

The truss wires 7 employed in carrying out the construction of the frame embody 95 an essential part of the construction as will be observed, and extend throughout the length of the frame and are diagonally arranged in respect to the bars 1 and are crossed in such a manner as to cause their 100 connected portions to overlap at the outer edges of the bars as clearly shown. The free ends of the truss wires 7 are bent over and brought into engagement with the notched upper and lower ends of the bars 105 1, whereby the said truss wires closely embrace and contact with the structure previously described. As clearly shown in Fig. 3 the lower ends of the truss wires 7 are formed upwardly after engaging with the 110 lower notched ends of the bars and are extended inwardly, whereby yielding anchors

8 are formed and are provided with downwardly projecting pointed hooks 9 which are embedded in the cement during the complete formation of the post. The meeting 5 and connected ends of the truss wires 7 at the opposite ends of the structure are similarly formed whereby the anchors referred to are arranged in a practical manner for the purposes described, and further it will 10 be observed that the parts comprising said structure are uniformly and bindingly arranged with respect to one another. The truss wires 7 not only retain the complete formation of the post but further hold the 15 binding bands in their proper position upon the angle bars 1, whereby the same are properly positioned.

From the foregoing description taken in connection with the accompanying drawings, 20 the construction and operation of the invention will be readily understood without requiring a more extended explanation.

Various changes in the form, proportion 25 and the minor details of construction may be resorted to without departing from the principle or sacrificing any of the advantages of the invention defined and claimed.

Having thus described my invention, what I claim as new is:

30 1. A reinforcing frame comprising a plurality of bars, means for connecting the bars and properly separating the same in respect to one another, and diagonally arranged truss wires spirally arranged on the outside 35 of said bars and bindingly in contact therewith, and having their ends interlockingly engaged with the opposite ends of said bars, the lower ends of the two wires being extended inwardly to form anchors.

40 2. A reinforcing frame comprising a plurality of bars, means for connecting the bars and properly separating the same in respect to one another, and diagonally arranged truss wires spirally arranged on the 45 outside of said bars and bindingly in contact with the outer edges of said bars and frictionally contacting with the bands, and having their ends bindingly and interlockingly engaged with the opposite ends of said 50 bars, the lower ends of the two wires being

extended inwardly and upwardly and provided with downwardly projecting anchors.

3. A reinforcing frame for cement constructions, comprising a plurality of angle bars having upper and lower beveled ends, 55 binding bands arranged in pairs and positioned at predetermined distances along the length of the bars for uniting the same and properly positioning the same in respect to one another, means for connecting said bands and binding the same against the bars, diagonally arranged truss wires extending the full length of the bars and overlapping and bindingly engaged with the bands, notches formed in the beveled ends 60 of the bars with which the opposite ends of the truss wires are bindingly and interlockingly engaged, the lower ends of said truss wires being extended upwardly and inwardly and provided with downwardly projecting hooked ends forming yielding anchors for engagement with the cement employed in the final completion of the structure.

4. A reinforcing frame for cement constructions, comprising a plurality of angle bars having upper and lower beveled ends, 75 binding bands arranged in pairs and positioned at predetermined distances along the length of the bars for uniting the same and properly positioning the same in respect to one another, means for connecting said bands and binding the same against the bars, diagonally arranged truss wires extending the full length of the bars and overlapping 80 and bindingly engaged with the bands, the ends of said two wires being arranged in the notches formed in the beveled ends of the bars, and anchors formed by the lower connected ends of the truss wires and inwardly projected and adapted to engage 85 with the cement completing the structure.

In testimony whereof I have hereunto set my hand in presence of two subscribing witnesses.

ALEXANDER FLEMING.
